UNITED STATES PATENT OFFICE

JOSEPH P. BARRON, OF KNOXVILLE, PENNSYLVANIA

COMBINED TRAFFIC INDICATOR AND ADVERTISING DEVICE

Application filed August 21, 1931. Serial No. 558,576.

This invention relates to traffic lights and has for the primary object, the provision of means mounted on a traffic light casing or housing for the purpose of permitting the 5 various colored lights to be more readily distinguished from each other and which provides a very efficient means on which advertisements may be displayed.

Another object of this invention is the 10 provision of a combined traffic indicator and advertising device which will be simple, durable and efficient and which may be manufactured and sold at a comparatively low cost.

With these and other objects in view, this 15 invention consists in certain novel features of construction, combination and arrangement of parts to be hereinafter more fully described and claimed.

For a more complete understanding of my 20 invention, reference is to be had to the following description and accompanying drawing, in which

Figure 1 is a side elevation illustrating a 25 combined traffic indicator and advertising device constructed in accordance with my invention.

Figure 2 is a top plan view illustrating the same.

Figure 3 is a plan view illustrating one of 30 the panels before being applied to the signal casing.

Referring in detail to the drawing, the 35 numeral 1 indicates the conventional type of signal casing used for the purpose of directing traffic at street intersections and as shown in Figure 1 may be supported by a post 2 or any other suitable supporting means. The direction signal above described is adapted 40 to display different colored signals at opposite sides thereof and to render these signals more distinguishable, panels 3 are provided. Each of the panels is constructed from a strip of metal having its ends rounded and provided with an opening 4 intermediate its 45 ends to be placed over the lens holder of the traffic signal. The panel is riveted or otherwise secured to the casing and is bent on the dotted lines as shown in Figure 3 to extend angularly to the side faces of the casing and 50 in alignment with the corners of the casing.

The panels may be colored to agree with the color of lights associated therewith to render the signals more extinguishable and the panels may have printed, painted, or otherwise applied thereto advertisements so that the 55 traffic signal besides giving signals will provide an efficient means for displaying advertising matter.

The walls of the signal casing above and below the panels 3 may have names or characters applied thereto and the walls of said casing are preferably coated black so that the different colored panels and signal lights will be more easily read or noticed.

The rounded portions at the top and bottom of the signal casing are the ends of the vertical walls of said casing.

While I have shown and described the preferred embodiment of my invention, it will be understood that minor changes in construction, combination and arrangement of parts may be made without departing from the spirit and scope of my invention, as claimed.

Having thus described my invention, what I claim is:

In combination with a traffic signal casing having different colored signals at the sides thereof and having the sides coated a dark color, a plurality of panels secured to the opposite sides of the casing and each having 80 an opening registering with the signals, said panels colored in accordance with the color of the signals and each panel bent angularly to provide portions projecting outwardly from the casing and in substantial alignment 85 with the corners of said casing, said portions adapted to have advertisements applied thereto.

In testimony whereof I affix my signature.

JOSEPH P. BARRON. 96
